UNITED STATES PATENT OFFICE.

ISAAC J. WISOFF, OF BROOKLYN, NEW YORK.

SOFA BEDSTEAD.

Application filed June 20, 1921. Serial No. 478,914.

This invention relates to an improvement in sofa-bedsteads, that is, an article of furniture adapted to be used as a sofa or as a bed according to the positions of some of its parts.

An object of this invention is to provide a sofa-bedstead which is exceedingly simple, and is of such construction that the parts which carry the seat and the back also directly support the mattress when the sofa is converted into a bed. Thus the number of parts and the cost and time of manufacture are reduced to a minimum, the addition and mounting of extra members or attachments to permit the adjustments required is avoided; no complicated structure is obtained; and at the same time a very neat, finished and comfortable sofa or bed, which can be made as ornamental or attractive as one may wish, is produced, and all the manipulation necessary to produce the desired result can be easily and quickly effected.

Other objects and advantages of this invention will appear from the following description taken with the accompanying drawings, which show the best form of the invention now known to me; and the characteristics of my invention are defined in the appended claim. This disclosure however, is explanatory only and I may change the construction actually shown herein, particularly as to shape, size and arrangement of parts, without departing from the nature of the invention, to the full extent indicated by the broad and general meanings of the terms in which the claim are expressed.

On the drawings:

Figure 1 is a front view of a sofa-bedstead according to my invention, ready to be used as a sofa;

Figures 2 and 3 are respectively side and back views of same;

Figure 4 is a section on line 4—4, of Figure 1; showing the parts carrying the seat and back, and capable of movement to convert the sofa into a bed, in position to make the sofa-bedstead serve as a sofa; the spring mattress utilized, when the sofa is converted into a bed, being omitted for the sake of clearness;

Figure 5 is a section in the same plane showing the same parts as Figure 4; but with the parts carrying the back and seat extended to make a bed;

Figure 6 is a top view of the entire structure extended to make a bed, the spring mattress being included; and

Figure 7 is a view of a detail.

The same numerals identify the same parts throughout.

In the detailed description of the sofa-bedstead illustrated in the drawings, I use the numeral 1 to indicate the framework which supports the various parts, while 2 indicates a cushion normally disposed in the lower part of the framework to serve as a seat, and 3 indicates a similar cushion, normally extending upward from the rear edge of the cushion 2 to provide a back. When the seat 2 and back 3 occupy the relative positions shown in Figures 1, 2 and 3 for example, the entire construction can be used as a sofa; but when the parts which support the seat 2 and back 3 are extended as indicated in Figures 5 and 6, the construction is in readiness to serve for a bed. The parts of the sofa-bedstead which carry the seat 2 and back 3 will then be in line with each other with the faces of the cushions turned downward towards the floor, and the said parts will then support an extended spring mattress 4, (see Figure 6), on which cushions or a mattress of felt, bedding, etc., can be spread to make a comfortable resting place. When the parts carrying the seat 2 and back 3 are folded together to hold the seat and back in the positions they should occupy when the structure is used as a sofa, the mattress 4 is folded inside of the sofa-bedstead as illustrated in Figure 7, and rendered entirely invisible, in a manner that will be hereinafter fully set forth.

The framework 1 comprises a pair of front legs 5, united by a cross piece or bar 6, and a pair of rear legs 7 united by a cross piece 8. The legs 5 and 7 and the cross piece 6 may be of wood, while the rear cross piece 8 may be of angle iron; and angle bars 9 may run from the beam 6 adjacent the front legs 5 to the rear legs 7 at each side of the sofa-bedstead to join the ends of the cross beams 6 and 8 together. Side arms 10 are also present, extending from the rear legs 7 to the tops of the front legs 5 and the spaces between the legs 5 and 7, the arms 10 and the angle bars 9 at each end or side of the sofa-bedstead may be filled in by continuous panels 11 which may be of cloth, wood or

upholstery as desired. The rear legs 7 are of greater length or height than the front legs 5 and are joined at their upper ends by a top 12. A back 13 may be provided to join the legs 7 at the rear. This back extends from the cross piece 8 up to and above the rear ends of the arms 10 and the upper edge of this back may be in proximity to or may abut the lower edge of a folding panel 14; which, not only assists in hiding from view one end of the mattress 4 under the back 3 when the seat 2 and back 3 are disposed in position to give the apparatus the form of a sofa, but also serves as a foot board when the apparatus is extended to be used as a bed, as is hereinafter more fully described.

To the front ends of the angle bars or beams 9 are secured a pair of angle beams 15 by hinges 16. The angle beams 9 are fixedly mounted with one web of each beam vertical and extending downward and the other web horizontal; and the horizontal webs of these beams extend towards each other. In similar position are the angle beams 15, which are shown as having their horizontal webs attached to the horizontal webs of the beams 9 so that the beams 15 can be swung back towards the legs 7 to enable them to be folded down upon the tops of the beams 9 or in the opposite direction to bring them into line with the beams 9, the horizontal and vertical webs of the beams 9 and 15 then abutting. Further to the ends of the beams 15 remote from the beams 9 are affixed angle beams 17 by pivot pins 18, uniting the vertical webs, the joint being made in such a manner that the horizontal webs of the angle beams 17 will abut the horizontal webs of the beams 15 when the parts are in the positions shown in Figures 5 and 6. The ends of the horizontal webs of these beams 17, by abutting against the ends of the horizontal webs of the angle beams 15, limit the movement of the angle beams 17 so that when the beams 17 are moved into line with the beams 15 they cannot move any further. I may employ springs 19 on each side to unite beams 9 to the beams 15 below the hinges and similar springs 19 attached to the beams 15 and the beams 17 below the axis of the pins 18; so that when the sofa is extended the springs will act to keep the beams 9, 15 and 17 in alignment. The springs 19 adjacent the pins 18 are fixed to the vertical webs of the beams 15 and 17, inside, below the horizontal webs; and the springs 19 at the hinges 16 may be joined to the outside of the vertical webs of the beams 9 and 15; or, as shown in Figure 6, to the inside of the vertical ribs, but in this case projecting anchor pins 20 must be affixed to the vertical webs to enable the said springs to clear the horizontal webs and prevent the springs from interfering with the

folding down of the beams 15 on the beams 9. The mattress, of course, extends, all the way from the cross piece 8 to the ends of the beams 17 and the horizontal webs of the beams 9, 15 and 17 will be perforated to enable the mattress to be held in place. When the seat 2 and back 3 are folded into the framework 1, to convert the apparatus into a sofa, the mattress will be folded in the same manner as the beams 15 and 17, as indicated in Figure 7, and be completely covered and rendered invisible. The outer ends of the beams 17 will be joined by a cross piece 21 and to this cross piece the folding panel 14 will be secured by suitable hinges. The outer end or foot of the mattress 4 may be attached to the cross piece 21 in any convenient way.

The numeral 22 indicates legs on the angle beams 15 adjacent the hinges 18 which join them to the beams 17, and similar legs 23 are attached to the sides of the beams 17 adjacent the end cross piece 21. The legs 22 are fixed, while the legs 23 are pivoted. I prefer to make the legs 22 of the shape of an L, inverted when the beams 9, 15 and 17 are in line, as in Figures 5 and 6; the horizontal limbs joined to the outside of the vertical webs of the beams 15 and the vertical limbs overlapping the adjacent ends of the beams 17. The ends of the panel 14 are joined to links 24, pivoted to the corners of the legs 22 adjacent the hinges 18, so that when the beams 15 are swung into line with the beams 17, the legs 23 will be moved to support the outer ends of the beams 17, and the links 24 will act to turn up the panel 14 into the position of a foot board. The legs 23 each have a lateral projection 25 by which they are pivoted to the vertical sides of the beams 17 and the upper ends of these legs are joined by links 26 to the pivots of the links 24 pinning them to the panel 14. When the beams 15 and 17 are moved into line with each other and with the beams 9, the action of the links 24 in swinging the panel 14 into the position of a foot board causes the links 26 to pull on the upper ends of the legs 23 in such a manner as to swing the legs 23 outward and to make them project at right angles to the beams 17. When the cushions are placed on the mattress and some one lies down on the bed, the bars 15 and 17 rest accordingly on the legs 22 and 23 and the parts of the sofa-bedstead are supported as firmly as they should be.

Of course the seat 2 and back 3 can be made in any desired style and can be mounted on panels or frames 27 which will be made fast to the edges of the vertical webs of the angle beams 15 and 17. These cushions are indicated in broken lines in Figure 4, and in full lines on Figure 5.

In practice when the apparatus is to be used as a sofa the beams 15 are turned so as

to be folded down upon the beams 9, the seat 2 being thus disposed in horizontal position between the arms 10; while the beams 17 are turned up at the back, holding the cushion 3 in place at the rear edge of the seat. At this time, the beams 17 and cross piece 21 will lie in the space enclosed by the upper part of the legs 7 and the top; and thus the legs 23 and the links 24 and 26 will be snugly arranged in folded positions, between the upper parts of the legs 7 and the sides of the beams 17, and these legs and beams may be of such dimensions as to cover these legs and links completely. Even if these legs and links are not entirely covered, they will not project far enough to make one's back uncomfortable because of the presence of the cushion 3. These legs and links will then be wholly or partly hidden from view by the legs 7 except along their edges; which can be seen between the legs 7 and the beams 17; while the legs 22 may project upward along the inner faces of the sides 11 and the arms 10 adjacent the rear legs 7. The legs 22 can be made of metal and they will be out of the way entirely and not likely to interfere with any one seated on the seat 2. The spring mattress 4 under these conditions will extend from the cross piece 8 along the beams 9 to the hinges 16, then back to the pins 18 and up to the cross piece 21, (see Figure 7), thus being entirely enclosed and hidden from view but in such position that nothing more than the swinging forward of the back 3 with the beams 17 and the lifting of the seat 2 with the beams 15 are required to enable the beams 15 and 17 to be turned out in front and lowered and the legs 22 and 23 to rest upon the floor, in order to make the apparatus ready as a bed. This movement of the parts, of course distends the mattress 4 and the action of the links 24 pulls on the links 25 and swings the legs 23 into position. To convert the bed into a sofa the parts are merely moved backward in the same way.

If desired, cross pieces 28 may be used to unite the ends of the beams 9 and beams 15 adjacent the hinges 16, to close the front of the sofa bedstead below the seat 2. These pieces 28 may have opposed recesses as at 29,

to avoid interfering with the springs 19 adjacent the hinges 16.

The sofa-bedstead will thus be seen to be made up of the smallest possible number of parts; and when used as a sofa it presents a very neat and finished appearance, the same as an ordinary sofa. When it is used as a bed, the same parts which ordinarily support the seat and back will directly support the mattress, and the cushions which are laid down on it. No cumbersome or complicated attachments are therefore used, and the apparatus can not only be manufactured at a low cost and at a minimum of time and labor, but it also is very easy to manipulate, to enable it to be used either as a sofa or a bed as the occasion demands.

As will be understood the sofa-bedstead will be given various ornamental forms and can be made in various sizes and with its dimensions varied to suit. The drawings show it wider in front than at the back, with the seat 2, supported on the beams 15, of such shape as to fit snugly between the sides 11, but obviously the same width may be given to both back and front whenever desired.

Having described my invention, what I believe to be new and desire to secure and protect by Letters Patent of the United States, is:—

A sofa-bedstead comprising a framework, parts for carrying a seat having hinged connection with the front of the framework, parts for carrying a back having hinged connection with the parts for carrying a seat, the parts for carrying the back and the parts for carrying the seat being movable into line with each other, springs connected to the parts for carrying the seat and the parts for carrying the back, and cross-pieces attached to the front of the framework and the parts for carrying the seat adjacent the front of the said framework, said crosspieces having opposed recesses to register and receive said springs, when the parts are extended, as set forth.

In witness whereof, I have signed my name to this specification, the 2nd day of May, 1921.

ISAAC J. WISOFF.
